UNITED STATES PATENT OFFICE

FRANK F. HILL, OF EMBARRASS, MINNESOTA

DISK-HARROW SHARPENER

Application filed January 16, 1928. Serial No. 247,143.

This invention relates to new and useful improvements in sharpening devices for disk harrows and aims to provide a relatively simple and inexpensive sharpening mechanism that may be applied to generally conventional disk harrows and this without in any manner whatever altering the construction of said harrows.

Furthermore by reason of the present invention there is provided means for simultaneously sharpening the edges of all of the disks of the harrow, and this without requiring the harrow operator to personally retain in his grasp or to maintain depressed any levers or the like during the sharpening operation.

In the drawings wherein like reference characters indicate corresponding parts throughout the several views:

20 Figure 1 is a rear elevation of a generally conventional disk harrow equipped with my sharpening means.

Figure 2 is a fragmentary side elevation thereof.

25 Figure 3 is a fragmentary top plan.

Figure 4 is a perspective of one of the supporting arms or brackets for the sharpening mechanism.

30 Figure 5 is a perspective of a hand lever provided for the movement of the sharpeners per se into or out of engagement with the disk.

Figure 6 is a fragmentary edge view of one of the disks and in engagement with which is the complementary abrasive slots, and

35 Figure 7 is a section through one of the blocks and its carrying arms.

Now having particular reference to the drawings, A designates the usual horizontal frame bar of a disk harrow beneath which is suspended a parallel harrow shaft or axle B which is equipped with a plurality of spaced harrow disks C.

40 In carrying out the present invention the inner ends of a pair of relatively elongated attaching brackets 5—5 are secured to the harrow frame bar B adjacent the opposite ends thereof, said brackets extending rearwardly at right angles to the frame bar as

clearly disclosed in Figures 2 and 3. The rear ends of these brackets 5 are downturned as at 6 and secured to said downturned ends of the bracket is a cross bar 7 to the outer face of which are pivotally secured depending arms 8 similar in number to the number of disks C, and being pivoted to the bar 7 directly at the edges of the disks as disclosed in Figure 1. The lower ends of these arms 8 terminate substantially centrally of the disk and are twisted a one-quarter turn as shown. To these lower twisted ends of the arms are bolted or otherwise rigidly secured abrasive blocks 9, the inner face of each of which is serrated as at 10, said serrated faces adapted for engaging the cutting edges of the disks C in tangential relation as disclosed in Figure 6 this being due to the one-quarter twist of the lower ends of said arms 8.

All of said arms 8 are interconnected by 70 a connecting bar 11 so that they will swing simultaneously upon the main bar 7 of the sharpening structure.

The abrasive blocks of the arms 8 are normally maintained in engagement with the cutting edges of the disks 7 through the medium of retractile coil springs 13 anchored at their opposite ends to the bar 7 and to said bars 8 above the connecting bar 11 as disclosed in Figure 1. Pivoted to the center of the bar 7 is a hand lever 14, the lower end thereof having pivotal connection with the connecting bar 11 for the obvious purpose of permitting the bar 11 to be swung in a direction toward the left for so moving the arms 8 as to disengage the abrasive blocks from the disks as disclosed by the dotted lines in Figure 1.

Arranged upon the upper edge of the bar 7 at the side of the lever 14 in the direction of the pull of the springs 13 is a beveled latch plate 15 over which said lever will ride when swung in the direction of the dotted line position to retain the abrasive blocks out of engagement with the disk C when the sharpening operation is not desired.

In view of the foregoing description when considered in conjunction with the accompanying drawing it will be apparent that I have provided a highly novel, simple and in-

expensive sharpening means for disk harrows that is well adapted for all the purposes heretofore designated, even though I have herein shown and described the invention as consisting of certain detail structural elements it is to be understood that minor changes may be made without departing from the spirit and scope of the appended claims.

Having thus described the invention, what I claim as new is:

- 10 1. In a sharpening device for disk harrows including a frame bar, a supporting bar mounted upon and in spaced parallel relation with the frame bar of the harrow, a plurality of arms pivoted to the frame bar and depending therefrom, said arms being similar in number to the number of the harrow disks and being mounted upon the bar adjacent said disks, an abrasive block arranged upon the lower end of each arm, means for normally so swinging the arms as to cause the blocks to have engagement with the edges of the disks, and manual control means whereby the arms may be swung away from the disks and locked in such a position.
- 20 2. In a sharpening device for disk harrows including a frame bar, a supporting bar mounted upon and in spaced parallel relation with the frame bar of the harrow, a plurality of arms pivoted to the frame bar and depending therefrom, said arms being similar in number to the number of the harrow disks and being mounted upon the bar adjacent said disks, an abrasive block arranged upon the lower end of each arm, means for normally so swinging the arms as to cause the blocks to have engagement with the edges of the disks, manual control means whereby the arms may be swung away from the disks and locked in such a position, said means consisting of a lever pivoted to the frame bar and having connection with the arm interconnecting bar and a latch plate upon the frame bar in back of which the hand lever may be engaged after swinging the arms away from said disks.

In testimony whereof I affix my signature.

FRANK F. HILL.
